SEPTIC TANK

William M. Bower, Suffield, Conn., assignor to
Bangor Punta Operations, Inc., Greenwich, Conn.

Filed May 17, 1973, Ser. No. 361,353

Term of patent 14 years

Int. Cl. D23—01

U.S. Cl. D23—2

FIG. 1 is a side elevation of a septic tank showing my new design, the opposite side being a mirror image of the side shown.

FIG. 2 is a top plan view thereof.

I claim:

The ornamental design for a septic tank, substantially as shown and described.
